UNITED STATES PATENT OFFICE.

HARRY MORTIMER SPECHT, OF NEW YORK, N. Y.

APPARATUS FOR MAKING FILAMENT FROM VISCID OR VISCOS SUBSTANCE.

1,310,509.

Specification of Letters Patent. Patented July 22, 1919.

Application filed January 12, 1918. Serial No. 211,559.

To all whom it may concern:

Be it known that I, HARRY MORTIMER SPECHT, a citizen of the United States of America, and resident of New York, in the 5 county of New York, in the State of New York, have invented new and useful Improvements in Apparatus for Making Filament from Viscid or Viscous Substance, of which the following, taken in connection 10 with the accompanying drawings, is a full, clear, and exact description.

This invention relates to certain improvements in apparatus for making filament from viscid or viscous substance, such as 15 cellulose, or any other fluent or semi-fluent which is susceptible of being reduced to a fibrous or ciliary state by forcing it under pressure through one or more capillary pores, and is particularly adapted for forming 20 the filamentous fiber from which the threads of artificial silk are made.

In the manufacture of artificial filament or fiber of this character, it is highly important that the capillary pore or pores, and 25 particularly the delivery ends thereof, be kept free from accretions of the same substance or foreign matter in order to preserve the sheen or luster and texture of the filamentous fiber, and one of the primary objects 30 of my present invention is to provide what may be termed a mechanical spinneret which will automatically reduce to a minimum the liability of such accretions, or if they should tend to accumulate may be readily dislodged by the finger or other wiping 35 instrument without retarding the progress of the work or displacing any of the mechanism of the apparatus.

Another object is to assemble a multiplicity of these spinnerets (according to the 40 number of filaments required for the thread) in such manner that the individual fibers may be automatically collected into a single strand for further treatment in their preparation for the manufacture into a fabric.

A further object is to construct each spinneret and its support in such manner that when assembled they will effectively resist the pressure incidental to forcing the viscous 50 substance therethrough, and at the same time permit any one of the spinnerets to be removed and replaced in case it should become broken or otherwise impaired.

Other objects and uses of the apparatus 55 will be brought out in the following description.

In the drawings—

Figure 1 is an end view of one form of apparatus for simultaneously producing a multiplicity of individual filaments used in 60 making a single thread or strand.

Fig. 2 is a longitudinal sectional view of the same device taken on line 2—2, Fig. 1.

Fig. 3 is an end view of a modified apparatus for producing a multiplicity of individual fibers in and around a common 65 axis.

Fig. 4 is a longitudinal sectional view of the modified device taken on line 4—4, Fig. 3.

Fig. 5 is a perspective view of one of the 70 detached capillary tubes or spinnerets.

The apparatus shown in Figs. 1 and 2 comprises a series of, in this instance nine, capillary tubes or mechanical spinnerets 75 —1— which, in this instance, are made of glass and are removably mounted in separate individual supports or holders —2—, preferably of lead or other relatively soft material to reduce the liability of breaking the glass tubes —1—, said holders being also 80 removably mounted in the outer ends of a corresponding number of branch pipes or nipples —3— of a main distributing head —4— having a supply pipe —5— for the viscous substance leading to the interior 85 thereof and are held in operative position by screw caps or nuts —6— on the outer ends of the nipples so that the holders with the capillary tubes or spinnerets therein may be removed or replaced when desired by simply 90 removing the nuts.

The nipples —3— are preferably of the same size and form and are detachably secured to one side of the distributing head 95 —4— for removability and replacement when desired or necessary and are disposed side by side in parallelism and in the same straight line lengthwise of the axis of the head —4— so that when the holders —2— with the capillary tubes —1— therein are 100 assembled, the delivery ends of the capillary tubes or spinnerets will also lie in the same straight line and in approximately the same plane at right angles to the axes of the nipples —3—.

The distributing head —4— is provided with a central lengthwise bow or passage —4'— communicating with the passages through the several branches —3—, the opposite ends of the passage —4'— being closed by coaxial screw plugs —7— which may be removed at any time to permit the

interior of the distributing head to be thoroughly cleansed when necessary.

In like manner, access may be had to the interior of the several passages —3— for cleansing purposes by simply removing the screw caps —6— and holders —2— with the spinnerets therein.

In Figs. 3 and 4, a plurality of, in this instance seven, of these capillary tubes or spinnerets are shown as mounted in a single holder —2— in and around a common axis, said holder being mounted upon the open end of a circular distributing head —4— and held in place by a screw cap —6—, said head being also connected to a supply pipe —5— leading to the interior thereof for directing the viscous substance through the spinnerets.

The capillary tubes or spinnerets are all alike; each one consisting of a slightly tapered main body snugly, but removably, fitted in a correspondingly tapered opening in its holder —2— or —2'— and having its delivery end still further, but more abruptly, tapered to an approximate point or diameter of the capillary passage, as —1'—, which is of the same diameter from end to end of the tube and therefore cylindrical, the opposite end of the tube being enlarged by an annular flange —1''— which is seated in a corresponding socket in the inner face of the holder to engage the end wall thereof, and thereby prevent outward displacement in the direction of projection of the viscous substance through the tube, but permitting it to be drawn endwise from said holder for replacement when impaired or for any other purpose.

The tapered points of the delivery ends of the capillary tubes or spinnerets when adjusted for use project beyond the adjacent end faces of their respective holders and are, therefore, free from contact with external objects which together with the taper and extremely small area of the delivery point from which the viscous fiber is projected reduces to a minimum the liability of accumulations or accretions of the same material or other foreign matter around and upon said point, thereby preserving the sheen or luster on the surface of the filament as produced by its passage through the capillary pore of the tube.

It is, of course, obvious that the number of spinnerets employed may vary at will according to the number of individual fibers required for a strand or thread, and that their relative arrangement may be varied without departing from the spirit of the invention, the main requirement being that the individual fibers be projected in the same or approximately the same direction so that they may be readily gathered together for

further treatment or equivalent manipulation in the formation of strands or threads 65 to be used as the weft in the manufacture of artificial silk or other fabrics.

In operation, when the parts are assembled in the manner described, the viscous material is forced under suitable pressure through the supply pipe —5— into the distributing head, as —4— or —4''—, and thence through the several capillary tubes so as to emerge from the points of said tubes in the form of filaments which, during the progress of 75 emergence, may be treated in any suitable manner, not shown or contemplated herein, for imparting to the fiber the necessary pliable tenacity for its further use.

In case there should be any tendency of 80 the material or foreign matter to accumulate around and upon the points of the capillary tubes, it may be readily removed by wiping contact of the finger therein or by any other instrument.

It will be noted that the identity of form and size of the spinnerets enables them to be readily interchanged from one support to the other, and also reduces the cost of manufacture and maintenance of the apparatus as a whole.

Another advantage is that owing to the smallness of the spinnerets, a multiplicity of them may be arranged in or upon the same support in relatively small compact 95 space with their conical ends in substantially the same transverse plane always accessible for cleaning the capillary bores terminating in the apexes of their respective cones, thereby not only reducing accumulations of the 10 same or foreign matter thereon as the filaments exude from the tubes, but also reducing the liability of air pockets being formed at the exit which might materially interfere with the perfect formation of said filaments. 105

What I claim is:

1. In a device of the character described, a holder having a tapered opening therethrough in combination with a spinneret having a tapered body fitted in said opening 110 and an enlarged head seated against the inner face of the holder.

2. In a device of the character described, the combination of a tubular distributing head having a series of radial branches in 115 one and the same straight line, each branch having a separate cap screwed thereon, separate holders clamped between the caps and their respective branches and mechanical spinnerets mounted in said holders.

In witness whereof I have hereunto set my hand this 29th day of December, 1917.

H. MORTIMER SPECHT.
